ACTUATING MEANS FOR KNITTING MECHANISM

Paul Schmidt, Wyomissing, Pa., assignor to Textile Machine Works, Wyomissing, Pa., a corporation of Pennsylvania

Application November 4, 1936, Serial No. 109,086

8 Claims. (Cl. 66—129)

My invention relates to novel mechanism for operating elements of knitting machines at different speeds, and particularly to mechanisms for operating friction boxes by friction rods at different speeds in a straight machine for knitting a full-fashioned stocking blank or the like.

In a machine for knitting full-fashioned stocking blanks, certain yarn carriers operate to lay ground yarn entirely across the blanks, and others to lay additional yarns for short distances over, or with, the ground-yarns, as in the heel areas to reinforce the blanks at these locations; these carriers all being operated by one friction rod. Thus, in knitting a blank to have double-yarn heel areas, at least three yarn carriers are required, one to lay the full courses and two to lay the heel reinforcing yarns.

In a ringless stocking having this double-yarn heel reinforcement, five carriers are employed, with three for laying single yarns in sequence for the full courses and two for laying the heel reinforcements.

In knitting a blank to have triple yarn heel areas, at least five yarn carriers are required, and, in a ringless stocking this number is increased to seven; all operated by the one friction rod.

In modern practice the machine is operated at very high speeds, so that the heat of friction between the several friction boxes and the single friction rod is substantially increased and has become a serious problem, with respect to which a number of remedies have been suggested.

Among the objects of my invention are to reduce the above-mentioned frictional heat and the damaging results thereof.

Another object is to provide a mechanism for operating different elements of a knitting machine at different speeds by a mechanism of materially enhanced simplicity and reduction in the number of its parts.

A further object is to provide a device of the above indicated character that is durable in construction, economical to manufacture and effective in its operation.

With these and other objects which may be incident to a utilization of the improvement, the invention comprises the parts and combinations thereof, which may be varied in shape, texture, relation and other features, and the operation, which may be varied, in accordance with the spirit and scope of the invention as hereinafter set forth and claimed.

Although means are shown in the accompanying drawings for carrying the invention into practical effect, these are merely by way of example,

without limiting the invention in its useful applications to the particular constructions which for the purpose of explanation are made the subject of illustration.

In the drawings:

Figure 1 is a view, in rear elevation, having distance breaks, of portions of a full-fashioned knitting machine embodying the invention, elements being broken away and omitted;

Fig. 2 is an enlarged view, taken along the line 2—2 of Fig. 1, parts being omitted;

Fig. 3 is an enlarged detail plan view of friction box and carrier bar portions of the machine, substantially as viewed in the direction of, and between, the arrows along a line 3—3 of Fig. 1; 15

Fig. 4 is a view taken along the line 4—4 of Fig. 3;

Fig. 5 is an enlarged view, taken substantially along the line 5—5 of Fig. 1;

Fig. 6 is a view, partially in elevation and partially in section, of a portion of the structure of Fig. 5, taken at right angles thereto; and

Fig. 7 is a diagram of portions of a full-fashioned stocking leg blank, and of the adjacently associated yarn-laying elements of the machine. 25

In practicing the invention, mechanism is provided for operating a knitting mechanism and a full-course yarn carrier in usual relation, and simultaneously operating reinforcing carriers at a reduced speed, such as half the speed of the 30 full-course carrier or carriers. This action is obtained by the use of a half-speed friction rod, which is auxiliary, or in addition, to a usual friction rod of a full-fashioned knitting machine. Further, means are provided whereby each of a 35 plurality of yarn carriers may be connected either to the usual friction rod or to the half speed rod as desired.

Preferably, a simplified speed-reducing mechanism is provided of the type disclosed and claimed 40 in the patent to Waechtler and Suess, No. 2,059,667, granted November 3, 1936 and having a reduced number of parts. Such mechanism has a single coulier motion mechanism including only one long or main rocker arm by which the main 45 or full-speed friction rod is operated, and to which the above-mentioned reduced-speed friction rod is directly connected independently of the connection between the main friction rod and the rocker arm. The full and reduced speed friction rods are connected positively to the rocker arm. The ratio of the different speeds is adjustable. These features severally and in combination constitute means of materially advantageous 50

character in the knitting art, but form no part of the present invention.

The figures exemplify the elements of the invention, and also only such elements of a "Reading" full fashioned knitting machine as necessary to an understanding of the invention. The other members of the machine and the operation thereof are well known, as set forth in the "Reading" Full Fashioned Knitting Machine Catalogue, copyright 1935, and published by the Textile Machine Works, Reading, Pennsylvania.

Referring particularly to Fig. 1 of the drawings, the frame work or base support of a standard full fashioned knitting machine therein indicated, comprises center frames 10 and end frames 11 rigidly positioned in spaced relation by a front rail 12, a back rail 13 and a center bed 14.

A coulier motion mechanism C of well-known type, comprises a draw bar or pitman 15, on which are mounted a pair of rollers 16 (only one of which is shown) for cooperation with a coulier cam 17, to oscillate a small rocker arm (not shown) and a large rocker arm 19. This mechanism operates to translate the rotary movement of the cam shaft into the reciprocable movements of the yarn feeding and loop forming mechanisms.

The rollers 16, adjustably secured to the draw bar 15, cooperate with the coulier cam 17 to reciprocate the draw bar, which is pivotally connected at its ends to the small and large rocker arms, respectively. The rocker arms are pivotally mounted on brackets, which are mounted on the back rail 13, one of these brackets 24 being shown in Fig. 1, for supporting the large rocker arm 19.

Reciprocation of the draw bar 15, oscillates the large rocker arm 19 about its lower end pivot, and reciprocates a cross head 27 through a link 28, the ends of which are pivoted to the large rocker arm 19 and to the cross head 27, respectively. The cross head 27, which is fixed to a full-speed friction rod 32, is carried by a slur cam connecting rod bracket 29 that is slidably mounted on a stationary guide 30.

A bracket or pivot support B is slidably reciprocably mounted on a back narrowing shaft 34 and comprises upper and lower portions 36 and 37 secured together, as by bolts or screws. The lower portion 37 has a depending arm 38 having a vertical slot 39 therein in which a pivot support 42 for one end of a link 43 is mounted for fixed adjusted position in any part of the slot. The other end of the link 43 is similarly mounted in a slot 44 in the rocker arm 19.

The upper portion 36 of the bracket B rigidly supports a connector device T for yieldably connecting to the coulier motion mechanism a shock reducer rod 45 carrying collars 46, Fig. 7, and positively connecting a reduced-speed friction rod 47 to the coulier motion mechanism. A stationary rod 48, on which the connector T slides, is provided to support and prevent turning of the connector about the main support on the shaft 34. Also, a slide guide 51, Fig. 2, of fork shape secured to the arm 38 and embracing a back catch-bar shaft 52 is provided to assist the rod 48 to prevent turning of the connector T and the bracket B relative to the shaft 34.

As better seen in Figs. 5 and 6, the connector device T comprises a vertical plunger or detent rod 54 having a pointed or tapered lower end 55 for cooperation with a notch 56 in the shock reducer rod 46. The plunger 54 is vertically re-

ciprocably mounted in a member 57 with respect to which it is prevented from turning by a pin and slot device 58. A spring 59 operates between the plunger 54 and a bridge 62, which is supported by a pair of bolts 63 on the member 57, to bias the plunger 54 downwardly.

As indicated in Fig. 5, a positive connection is provided, as by a set screw 61, between the reduced speed friction rod 47 and the connector T to positively connect the rod 47 to the coulier motion mechanism.

Fig. 7 illustrates one application of the invention, in producing a full fashioned stocking leg blank S having reinforced heel areas L and R. Three friction boxes 64, 65 and 66 are shown, these boxes being identical except for a member 70 on the box 64 to be thrown into and out of the path of travel of the collars 46 on the shock reducer rod 45.

As better seen in Figs. 3 and 4, the box 65 is of double box character surrounding the closely adjacent parallel main and auxiliary friction rods 32 and 47, respectively, each half of the box being like a complete single box including the usual friction linings 71, shoes 72 and leaf springs 73, but the box halves being distinguished by a cam handle 75 on the full-speed half of the box, and a similar handle 76 on the reduced speed half of the box. A usual slide bar 78 on the box 65 having a handle 79 is adapted for selective cooperation with a dog 80 on any of the usual yarn-carrier bars 1 to 8, inclusive, on each of which a yarn-carrier or finger is adapted to lay yarn to a knitting head assembly K (Fig. 2) including the usual needle bank 81, sinkers, dividers and other elements. The carrier bars are supported by stationary brackets 82 on the center bed 14, and are provided with usual end stops S, Fig. 1. The boxes 64, 65 and 66 are connected to carrier bars 4, 5 and 6, Fig. 7, on which are mounted 40 yarn-carrier fingers 84, 85 and 86, respectively. In this instance, the boxes 65 and 66 are connected to the half-speed friction rod 47, and the box 64 is connected to the full-speed friction rod 32.

In operation, upon rotation of the coulier cam 17, the pitman 15 oscillates the rocker arm 19 about its lower-end pivot, whereby the link 28 at the upper end of the rocker arm, the slur cam connecting rod bracket 29, the cross-head 27 and the friction rod 32 are reciprocated at the speed of substantially the fastest moving part of the rocker arm through distances in accordance with oscillation of the rocker arm between lines a and b.

When both the high speed friction rod 32 and the low speed friction rod 47, are at the right hand ends of their strokes, corresponding to the position b of the rocker arm indicated in Fig. 1, with the ground yarn carrier rod 4 connected to 60 the friction box 64 operated by the high speed friction rod 32, and splicing yarn carrier rods 5 and 6 connected to friction boxes 65 and 66 operated by the low speed friction rod 47, these carriers will start laying their yarns at the same time, but, with the friction rod 32 traveling twice as fast as the rod 47, there will be a constantly changing relative speed between the carriers. Near the ends of the strokes, the member 70 will engage one of the collars 46 on the half-speed shock reducer rod 45 whereby the box 64 will slip relative to the high-speed friction rod 32 but will be carried thereby at the reduced speed until the carrier bars engage the end stops S. Upon impact of member 70 with a collar 46, the plunger 75

54 is momentarily lifted partially out of the notch 56 against the action of the spring 59 which thereby absorbs the shock of this impact, and subsequently presses the plunger back into normal position in the notch. At the ends of the 5 strokes of rods 32 and 47, the loops will be formed in a usual manner, whereupon the return strokes of the ground yarn carrier 4 and the splicing yarn carriers 5 and 6 will take place.

10 Although as many yarn carriers may be employed as in machines heretofore constructed, by the arrangement in which the splicing carriers are operated at only half the speed of the main carrier or carriers, the heat of friction is greatly reduced and the ability of the machine to run at 15 high speed in more effective manner is materially enhanced. This feature marks a desirable advance in the knitting machine art, and ensures the effective production of knitted fabric in accordance with a principle which to the best of my knowledge has not heretofore been known.

20 The improvement specifically shown and described, by which the results are obtained, may be modified in various ways, without departing 25 from the invention as set forth and claimed.

I claim:

30 1. In a straight knitting machine, loop-forming mechanism including a needle bank, yarn carrier means including yarn-carrier bars parallel to the needle bank, means for actuating the yarn carrier bars including a plurality of friction rods reciprocable at different speeds, and a single friction box for selectively connecting a carrier bar to one or another of said friction rods.

35 2. A straight knitting machine comprising loop forming mechanism including a needle bank, yarn carrier means including yarn carrier elements parallel to the needle bank, means for actuating the yarn carrier elements including a 40 plurality of members reciprocable at different speeds parallel to the carrier elements, means for adjusting the ratio of said speeds, and a single means for selectively connecting a carrier element to one or another of said members.

45 3. A straight knitting machine comprising loop-forming mechanism including a needle bank, yarn carrier means including yarn carrier elements parallel to the needle bank, means for actuating the yarn carrier elements including a 50 plurality of members reciprocable at different speeds parallel to the carrier elements, and a single means for selectively connecting a carrier element to one or another of said members.

55 4. A straight knitting machine comprising loop forming mechanism including a needle bank,

yarn carrier means including yarn carrier bars parallel to the needle bank, means for actuating the yarn-carrier bars including a plurality of friction rods longitudinally reciprocable parallel to the carrier rods, a friction box including 5 means for selectively connecting it to one or another of said friction rods, and means for connecting the friction box to one of the carrier bars.

5. A straight knitting machine comprising loop 10 forming mechanism including a needle bank, yarn carrier means including yarn carrier bars parallel to the needle bank, means for actuating the yarn carrier bars including a plurality of friction rods longitudinally reciprocable at different speeds parallel to the carrier rods, a friction box including means for selectively connecting it to one or another of said friction rods, and means for connecting the friction box to one of the carrier bars. 15

6. A straight knitting machine comprising loop forming mechanism including a needle bank, yarn carrier means including yarn carrier bars parallel to the needle bank, means for actuating the yarn-carrier bars including friction rods disposed in closely adjacent side-by-side relation and longitudinally reciprocable at different speeds parallel to the carrier bars, a friction box structure surrounding said friction rods, sets of friction shoes and clamps carried by the box for selectively connecting the box to one or another friction rod, and means for connecting the box to a carrier bar. 20 25 30

7. In a straight knitting machine, loop-forming mechanism, a plurality of yarn carrier bars, and means for operating the bars, said means including a high-speed friction rod, a friction box for connecting the high-speed friction rod to a yarn carrier bar, a low speed friction rod, and a friction box for connecting the low-speed friction rod to another carrier bar, one of said friction boxes being selectively connectible to the other of said friction rods. 35 40

8. In a flat knitting machine having a plurality of knitting sections, in combination, a plurality of friction rods operating at different speeds, a plurality of yarn carrier bars, and a plurality of friction box units mounted on said rods for driving said bars, each of said units having means for selectively establishing driving connection between either of said friction rods and any of said yarn carrier bars so that the latter may be operated at different speeds relative to each other in one or more sections of the machine. 45 50 55

PAUL SCHMIDT.

CERTIFICATE OF CORRECTION.

Patent No. 2,105,444.

January 11, 1938.

PAUL SCHMIDT.

It is hereby certified that error appears in the above numbered patent requiring correction as follows: In the heading to the drawings, Sheets 1 and 2, name of inventor, for "T. SCHMIDT" read P. SCHMIDT; and that the said Letters Patent should be read with this correction therein that the same may conform to the record of the case in the Patent Office.

Signed and sealed this 29th day of March, A. D. 1938.

(Seal)

Henry Van Arsdale,
Acting Commissioner of Patents.
